UNITED STATES PATENT OFFICE.

WALTER KELITA KAYE, OF LEEDS, ENGLAND.

LATCH FOR THE DOORS OF MOTOR ROAD VEHICLES.

Application filed March 10, 1926, Serial No. 93,566, and in Great Britain June 27, 1925.

It is well known in the motor car industry that it is desirable to have the doors, especially those of coupés and sedans, provided with latches which are easy to close and open 5 without submitting the same to undue strains and consequent wear and tear, and at the same time to provide safety catch devices which will prevent a door from flying open, should the same be not properly closed.

10 It is therefore my object to arrange and construct and combine with motor vehicle doors a latch mechanism with the necessary striker plate and safety catch which shall be efficient and will stand a test of time as to 15 wear and tear.

It has been customary in Great Britain to provide railway carriage doors with latches which have become known as the "Kaye" wedge locks, examples of which are disclosed 20 in the specification of British Letters Patent Nos. 17,210 of 1906 and 10,530 of 1888. In this latch one of the main characteristics is a wedge shaped bolt arranged in connection with what is known as a ram in such wise 25 that each serves to relieve the other of strain during operation. Further requirements led to the adoption of a safety catch in the striking plate, which catch was depressed by the latch bolt on the closing of the door, but 30 which projected and caught the slightly protruding bolt as the door tended to open, examples of safety catch patents in Great Britain are Numbers 10,522 of 1893 and 1,205 of 1908. Practice has however shown that a 35 pressing contact of the wedge shaped bolt against the immovable face of the safety catch has created a tendency of the bolt to move back into its casing and a continued opening pressure in certain circumstances tended to 40 open the door and defeat the desired object.

A safety catch and striking plate of the kind referred to along with the improved construction hereinafter described is adaptable to the doors of motor coaches and the like 45 and the resultant mechanism will stand considerable wear and tear and be easy of operation, owing to the absence of strain on the parts.

I accomplish my improvement by arranging 50 a safety catch in the striking plate in such wise that it will easily recede during the closing movement of the door without placing undue strain on the bolt and by forming that face of the bolt which engages the safety 55 catch, in the opening position, with a flat face which will meet and engage the safety catch

engaging face and overcome the tendency of the bolt to retire, or be pressed back within its casing.

It should be understood that the latch 60 mechanism is of the kind that when the opening handle is released after the bolt has left its housing in the striking plate, the wedge bolt automatically protrudes or tends to protrude to engage the safety catch. 65

The nature and operation of my invention are fully disclosed in the following specification and accompanying drawings in which similar reference letters indicate corresponding parts wherein:— 70

Fig. 1 represents a sectional plan of a door and door pillar showing the disposition of the latch parts, striking plate, and safety catch. 75

Fig. 2 represents a face view of a striking plate and safety catch.

Fig. 3 represents a sectional elevation through that part of the striking plate which carries the safety catch with the nose of the bolt in the engaging position. 80

Fig. 4 represents a face view of the latch showing bolt and ram. 85

Fig. 5 represents an elevation of the latch mechanism and striking plate from the interior of the vehicle and

Figs. 6 and 7 represent a plan and a side view respectively of a modified form of safety catch. 90

To carry my invention into effect. In Fig. 1 D represents a portion of the door and P the door pillar. The door D is usually hinged slightly to the outside to permit of a clearing action between the door and pillar as the same are slightly sloped from the inside to the outside as shown. In the form of latch shown 95 the casing L and inside handle mechanism H are fastened on the inside, a suitable spindle H' shown dotted connects to the outside handle H². The latch is of the old and well known type known as "Kaye's wedge type" 100 as shown for instance in British Patents No. 10,530 of 1888 and No. 15,595 of 1891, this type of latch having a sliding bolt B and a ram R. Inasmuch as the mechanism for operating the bolt and ram is old and forms no 105 part of the present invention, it is deemed unnecessary to illustrate the same herein. The striking plate S is mounted in the pillar P, a face view of the striking plate is shown in Fig. 2. This plate S is provided with a safety catch C, which is the essential feature 110 of the present invention, as hereinafter de-

scribed. On the safety catch engaging side of the bolt B is a flat B' formed towards its end, this flat is shown in Figs. 1 and 3.

In Fig. 1 the parts are shown with the door in its closed position but for the sake of clearness of illustration the gap between the door and striking plate is wider than it will be in actual practice.

In operation to open the door the bolt is operated in this case either by the sliding handle H on the inside or the handle H² on the outside. This movement withdraws the bolt B, and on release of the handle the bolt B has a tendency to remain slightly projected. If therefore the door be pressed towards the opening position without keeping the bolt in its innermost position, such bolt will contact with the safety catch and prevent the door from opening. This action will take place should the door be not correctly closed.

In closing the door it is not necessary to operate either handle. The door may be pushed or pulled to, in which case the protruding bolt B will engage the pivoted safety catch and depress the same in the direction of the closing of the door until it is cleared, the bolt B riding over the face C' of the catch C. Then the ram R in passing over the striking plate engages the same and at the same time the nose of the bolt B also engages the striking plate.

The ram R and bolt B move in, as described in the British patents hereinbefore referred to and this frees the bolt B and allows its springs to act to press out such bolt until it is housed in its recess or opening S' in the striking plate.

In order to operate easily and without undue strain on the parts, the safety catch C is pivotally mounted as at C² in the striking plate S, an aperture S² being provided for the purpose. The catch C is contained in a casing C³ suitably attached to the plates as in Fig. 3 and is operated by a spring C⁴. In order that the catch C cannot move too far out of its housing a projection C⁵ may engage the under edge of the plate S. In another form Figs. 6 and 7 the catch is provided with side projections C⁶ which will also contact with the underside of the plate S.

To prevent access of dust and dirt, the sloping face C' of the catch C is set back having a making up portion C⁸ to fill up to the apertures S².

The bolt B as before described is provided with a flat face B' and in the safety position this face will engage with the stop face C'.

This arrangement prevents any tendency of pressure between the parts to push the bolt B within the casing.

It is also preferred to limit the inward travel of the catch C within its casing C³ both to relieve the springs of undue pressure and to take strain off the cam catch. Thus when the catch is in the position its incline C' will be level, or nearly so, with the striking plate face, and the rear portion of the catch such as C⁹ Fig. 3 will contact with the casing C³.

The striking plate S and catch C will be in one fitting and be attached in any convenient manner.

S³ represents a cover fitting for the striking plate fastened to the pillar P on the inside.

A striking plate and safety catch as hereinbefore described will be found particularly adaptable for motor car doors and obviate many of the defects now experienced.

What I claim is:—

1. A door fastening device, comprising a striking plate mounted in the door frame and provided with a pair of recesses open toward the door opening, one of said recesses adapted to receive the door retaining bolt when projected, and a pivotally mounted spring-pressed safety catch disposed in the other recess and having a portion normally projecting beyond the outer surface of the plate, said catch being adapted to engage the bolt and stop movement of the door in the opening direction and to be pressed into its recess during the movement of the door in the closing direction.

2. A door fastening device, comprising a striking plate mounted in the door frame and provided with a pair of recesses open toward the door opening, one of said recesses adapted to receive the door retaining bolt when projected, and a pivotally mounted spring-pressed safety catch disposed in the other recess and having a portion normally projecting beyond the outer surface of the plate, said catch being adapted to engage the bolt and stop movement of the door in the opening direction and to be pressed into its recess during the movement of the door in the closing direction, said catch having means for limiting its movement.

In testimony whereof, I have signed my name to this specification at Leeds, Yorkshire, England, this 18th day of February, 1926.

WALTER KELITA KAYE.
